UNITED STATES PATENT OFFICE.

HENRY GUSTAV EISLER, OF WILMETTE, ILLINOIS.

HYDRAULIC JACKING SYSTEM.

Application filed October 10, 1925. Serial No. 61,821.

This invention relates to hydraulic jacking, pumping and oiling systems in general and more particularly to such systems as are adapted to be used on automobiles.

5 It is accordingly an object of this invention to provide an efficient hydraulic jacking, pumping, and oiling system which may be economically manufactured and conveniently operated.

10 Other and further important objects of this invention will be apparent from the disclosures in the specification and accompanying drawings.

15 The invention (in a preferred form) is illustrated in the accompanying drawings and hereinafter more fully described.

On the drawings:

Figure 1 is a side elevational view of an automobile having a system embodying this 20 invention installed thereon.

Figure 2 is a plan view with parts removed showing diagrammatically the connections to the various parts of the system.

25 Figure 3 is an enlarged fragmentary, diagrammatical, sketch showing the manner in which the various parts are connected together in the system.

Figure 4 is an enlarged fragmentary side elevational view with parts removed of the 30 pump, reservoir, release valve, distributing valve, and connections thereto.

Figure 5 is a side elevational view of Figure 4.

Figure 6 is an enlarged fragmentary vertical transverse section with parts omitted taken at the line VI—VI of Figure 4 and showing the release valve.

40 Figure 7 is an enlarged fragmentary vertical longitudinal section with parts omitted and parts in elevation taken at the line VII—VII of Figure 5 and also showing the release valve.

Figure 8 is an enlarged fragmentary vertical transverse section with parts omitted 45 and parts in elevation, taken at the line VIII—VIII of Figure 4 and showing the distributing valve.

Figure 9 is an enlarged fragmentary detail view with parts omitted showing the 50 distributing valve as viewed in Figure 4.

Figure 10 is an enlarged detail section with parts omitted taken at the line X—X of Figure 2 and showing the swing valve and jack.

55 Figure 11 is an enlarged fragmentary de-

tail view partly in section of a portion of the device shown in Figure 10.

Figure 12 is a view similar to that of Figure 11 and showing the same mechanism therein except that the jack and swing valve 60 are shown in downward or operative position.

Figure 13 is a fragmentary horizontal section with parts omitted taken at the line XIII—XIII of Figure 12.

65 A shown on the drawings:

The system of this invention comprises essentially a reservoir 1 containing a suitable fluid such as grease, oil or the like; a pump 2, a release valve 3, a distributing valve 4, and the various devices desired to be operated hydraulically including the jacks 5 and swing valves 6 associated therewith. The release valve 3 is connected in the system with the distributing valve 4 and the reservoir 1 and pump 2 so as to permit the latter 70

at one position of said release valve to put a suction on the distributing valve and discharge pressure on the reservoir and at another position of said release valve to put 75

a suction on the reservoir and a discharge 80 pressure on the distributing valve. The distributing valve is connected between the release valve and the various devices desired to be operated hydraulically for selectively connecting the release valve to said various devices.

85 For the sake of economy of space and construction, as well as for the sake of ruggedness, the reservoir 1 and the pump 2 are contained in a single casing 7. The pump 2 comprises a cylinder open at the 90 rear end and which extends longitudinally along the lower right-hand edge of said casing.

A piston 8 of the pump 2 is provided with a central rearwardly extending rod 9 which is pivotally connected at the 95 rear end thereof to a transverse lever 10, said rod being connected to said lever intermediate the ends of the latter.

The lever 10 is pivoted at its inner end to a bracket 12 secured on the rear side of the casing 7 100 and is provided with a handle 11 at its outer end through which the pump 2 may be operated.

The forward end of the pump 2 is connected through a pipe 13 to the upper portion of the housing of the release valve 3. A second pipe 14 is suitably connected at 105 one end thereof to the pipe 13. The other end of the pipe 14 communicates with the lower portion of the housing of the release valve 3 through a pair of parallel connec-

tions 15 and 16. The connections 15 and 16 have mounted therein one-way valves 17 and 18 respectively. The valves 17 will only permit fluid to flow therethrough in a downward direction; that is, said valve will automatically be opened when suction is placed thereon by the pump 2 and will automatically be closed when pressure is placed thereon by the pump 2. The valve 18 will only permit fluid to flow therethrough in the upward direction; that is, it will be closed when suction is placed thereon by the pump 2 and will be opened when a discharge is placed thereon by the pump 2. The reservoir 1 is connected to a pipe 19 which through a pair of parallel pipes 20 and 21 communicates with the housing of the release valve 3. Pipes 20 and 21 have mounted therein one-way valves 22 and 23 respectively. The connections for the pipes 20 and 21 with the housing of the release valve 3 are in the same circumferential plane as the connection for the pipe 13 and are equally spaced on either side of the latter. The valve 22 will only permit fluid to flow therethrough downwardly and the valve 23 will only permit fluid to flow therethrough upwardly. A pipe 24 is connected to the housing of the valve 3 in substantially the same circumferential plane with the connections for the pipes 15 and 16 and the connection therefor is centrally positioned intermediate of the latter two connections. The other end of the pipe 24 is connected to and communicates with the interior of the housing of the distributing valve 4. The release valve 3 is provided with a rotatable barrel 25 snugly fitting the interior of the valve housing and having a pair of diametrically opposed recesses 26 and 27. At one angular position of the barrel 25, that is the "on" position, the recess 26 will connect the ends of pipes 13 and 20 together inside the valve housing and the recess 27 will connect the ends of the pipes 16 and 24 together inside of said housing. At a second angular position of the barrel 25, that is the "off" position, the recess 26 will connect the ends of the pipes 13 and 21 together inside the valve housing and recess 27 will connect the ends of the pipe 24 and 16 together inside of said housing. The barrel 25 is provided with a central outwardly extending integral shaft 28 upon which may be secured a knob or lever 28^a for rotating said barrel to on or off position. The housing of the distributing valve 4 is cylindrical in shape and has connected thereto and communicating with the interior thereof a plurality of pipes 29, 30, 31, 32, 33 and 34. The connections for the pipes 29, 30, 31, 32, 33 and 34 are substantially in the same circumferential plane on the housing of the valve 4. A rotatable barrel 35 is provided in the valve 4, fits snugly in the housing thereof, and is pro-

vided with a central chamber 36 and a radial passage 37 extending from said recess to the periphery of said barrel. The aperture 37 is in substantially the same circumferential plane as the connections from the pipes 29, 30, 31, 32, 33 and 34 so that the barrel 35 may be selectively rotated to connect the chamber 36 with any of said pipes. The pipe 24 communicates with the chamber 36 in the housing of the valve 4 through a centrally apertured plate 38 secured on the inner face of said housing. A parallel plate 39 secured on the outer face of the housing of the valve 4 is apertured to receive therethrough a central outwardly extending shaft 40 integral with the barrel 35 and adapted to have secured thereon an operating knob or lever 40^a (Figure 2). The other end of each of the pipes 29, 30, 31 and 32 is connected to a swing valve 6, one mounted near each end of each axle of an automobile or other vehicle. Referring to Figures 1 and 10 there is shown rigidly clamped to an axle 43 a rearwardly and upwardly extending arm 41. Each arm 41 has an integral clamp 42 at the forward end thereof which is adapted to fit the side of an axle 43 and is flanged at the upper and lower edges for connection to a flanged member 44 fitting the other side of said axle and bolted to said first clamp member. A swing valve 6 previously mentioned is provided at the rear end of each arm 41 and consists essentially of a hollow cylindrical housing 45 open at either end and transversely journalled on said rear end. The rear end of each arm 41 is recessed to provide a transverse core 46 which extends from near one side of said arm part way to the other side thereof. The recess about the core 46 is enlarged to form an annular shoulder 47 concentric with the core 46 and to rotatably receive the housing 45, one side of which bears on said shoulder. A plate 48 which is recessed at its outer edges to provide a second annular shoulder 49 concentric with the core 46 and upon which the other side of the housing 45 bears, is rigidly secured to said core. The plate 48 effectually closes the outer side of the recess surrounding the core 46. A pair of angularly spaced upper and lower plates 50 and 51 respectively extend radially from the core 46 to form with each other, the periphery of said core and the inner periphery of the housing 45, an outer arcuate recess 52. The plates 50 and 51 effectually close the upper and lower ends of the recess 52. A radial lug 53 is provided integral with the housing 45 and extends from the inner periphery thereof across the recess 52 reaching to the periphery of the core 46. A hydraulic jack cylinder 54 is provided on the outer periphery of the housing 45 and integral therewith, the axis of said cylinder extending in a plane parallel to the planes of rota-

tion of said housing. A jack plunger 55 is contained in the cylinder 54 such that when the housing 45 is rotated clockwise as shown in Figure 10, said plunger and cylinder will move from the horizontal to an upright vertical position. The plate 50 and lug 53 are positioned to limit the anti-clockwise movement of the housing 45 as shown in Figure 11 and the plate 51 is positioned to limit the clockwise movement of said housing as shown in Figure 12. The end of each of the pipes 29, 30, 31, 32 and 33 opposite to the distributing valve 4 is connected to the side of the corresponding arm 41 adjacent the inner end of the core 46 and communicates through a passage 56 to the upper end of the recess 52. One end of a flexible pipe 57 is also connected to said arm 41 adjacent the foregoing connection thereto from one of the pipes 29, 30, 31, 32 or 33 and communicates through a passage 58 with the recess 52 adjacent the lower end thereof. The other end of the pipe 57 is connected to the top of the cylinder 54. There are thus provided four jacks one near each end of the front and rear axles of the vehicle. The jacks are normally carried in a horizontal position as shown in Figures 1, 2 and 10. The end of the pipe 33 opposite to the distributing valve 4 may be connected to a suitable air pump and the similar end of the pipe 34, in case a lubricant is used for a fluid in the system, may be connected to the various bearings desired to be lubricated.

In the operation when it is desired to operate any of the jacks 5 for raising the part of the car served thereby it is only necessary to manipulate the lever 40^a (Figure 2) of the distributing valve so as to rotate the barrel 35 until the proper jack is in communication with said valve. A suitable dial or indicator (not shown) is provided for indicating what positions of the lever 40^a will selectively connect the valve 4 to each of the pipes 29, 30, 31, 32, 33 and 34 respectively. The release valve 3 is then turned to "on" position so that when the handle 11 is operated to actuate the piston 8 to the left (Figure 3) the fluid from the reservoir may be drawn into the pump through pipes 19 and 20, valve 22 therein, recess 26 and pipe 13. When the piston 8 moves to the right the fluid will be discharged under pressure through pipes 13, 14 and 16, valve 18 in the latter, recess 27 and pipe 24 to the distributing valve chamber 36 whence it passes through the passage 37 to one of the pipes 29, 30, 31 or 32 to the proper jack. Before entering the jack 5 however the fluid first enters the passage 56 of the swing valve 6 associated with the jack and enters the recess 52 causing the lug 53 to move away from the plate 50. When the lug 53 has moved far enough to abut the plate 51 the jack 5 will have reached a vertical position.

When the swing valve 6 has moved the jack 5 to vertical position and the lug 53 has passed the opening of the passage 58 the fluid will enter said passage and the flexible pipe 57 to reach the top of jack cylinder 54 70 and force the jack plunger downwardly.

When the release valve 3 is turned to "off" position a suction may be placed on the distributing valve for communication to any of the devices which have been operated 75 hydraulically and the fluid drawn therefrom may be discharged to the reservoir 1. The suction communicated to the recess 52 will act to return the jack 5 to horizontal position but this action may be supplemented 80 by a spring (not shown) connected for normally holding the jack in said position.

It will be obvious that the foregoing system provides a means for jacking the car in a simple and convenient manner. 85

By providing four jacks the entire car may be raised at once, a convenience for storage, repairs, etc.

The rigidity with which the jacks are held in operative position will prevent the car 90 from tipping the jack over when moved slightly for any reason.

I am aware that many changes may be made and numerous details of construction may be varied through a wide range without departing from the principles of this invention, and I therefore do not purpose limiting the patent granted hereon, otherwise than necessitated by the prior art. 95

I claim as my invention:

1. A vehicle hydraulic system having connected therein a pump, a reservoir, hydraulic lifting means, and controlling means for permitting said pump to discharge to either the lifting means or the reservoir, said controlling means including a release valve and a distributing valve. 105

2. A vehicle hydraulic system having connected therein a pump, a reservoir, hydraulic lifting means, and controlling means for permitting said pump to place a suction on either the lifting means or the reservoir, said controlling means including a distributing valve and a swing valve, individual to each 110 of said lifting means.

3. A vehicle hydraulic system having connected therein a pump, a reservoir, hydraulic lifting means, and controlling means for permitting said pump to place a suction on the reservoir and discharge to the lifting means 120 or to place a suction on the lifting means and discharge to the reservoir.

4. A vehicle hydraulic system having connected therein a pump, a reservoir, a plurality of hydraulic devices, and means for selectively connecting said pump to said devices, said means including releasing means and distributing means independent of said releasing means. 125

5. A vehicle hydraulic system having con-

- 5 nected therein a pump, a reservoir, a plurality of hydraulic devices, distributing means selectively connected to said devices, and controlling means connected with said first means, said reservoir and pump for permitting said pump to discharge to either the first means or the reservoir.
6. A vehicle hydraulic system having connected therein a pump, a reservoir, a plurality of limiting devices operatively disposed on the vehicle for lifting the same, and means for selectively connecting said pump to said devices, said means including releasing means and distributing means controlled by said releasing means.
7. A vehicle hydraulic system having connected therein a pump, a reservoir, a plurality of lifting devices operatively disposed on the vehicle for lifting the same, distributing means selectively connected to said devices, and controlling means connected with said first means, pump, and reservoir for permitting said pump to discharge to either the first means or the reservoir.
8. A vehicle hydraulic system having connected therein a pump, a reservoir, a plurality of lifting devices operatively disposed on said vehicle for lifting the same, distributing means connected to said devices, and controlling means connected with said first means, pump, and reservoir for permitting said pump to place a suction on either the first means or the reservoir.
9. A vehicle hydraulic system having connected therein a pump, a reservoir, a plurality of lifting devices operatively disposed on said vehicle for lifting the same, distributing means connected to said devices, and controlling means connected with said first means, pump, and reservoir, for permitting said pump to place a suction on the reservoir and discharge to the first means, or place a suction on the first means and discharge to the reservoir.
10. A vehicle hydraulic system having connected therein a pump, a reservoir, hydraulic lifting means, controlling means for permitting said pump to discharge to either the lifting means or the reservoir, and means disposed between said lifting means and controlling means and operatively connected to the former means for normally holding the same in an inoperative, out-of-the-way position and for shifting the same to an operative position on the discharge of the pump thereto.
11. A vehicle hydraulic system having connected therein a pump, a reservoir, hydraulic lifting means, controlling means for permitting said pump to discharge to either the lifting means or the reservoir, and means disposed between said lifting means and controlling means and operatively connected to the former means for normally holding the same in an inoperative, out-of-the-way position and for shifting the same to an operative position upon the discharge of the pump thereto.
12. A vehicle hydraulic system having connected therein a pump, a reservoir, hydraulic lifting means, controlling means for permitting said pump to discharge to either the lifting means or the reservoir, and swinging means disposed between said lifting means and controlling means and operatively connected to the former means for normally holding the same in an inoperative, out-of-the-way position and for shifting the same to an operative position upon the discharge of the pump thereto, said lifting means being responsive to a predetermined movement of said swinging means.
13. A vehicle hydraulic system having connected therein a pump, a reservoir, a plurality of lifting devices operatively disposed on the vehicle for lifting the same, means for selectively connecting said pump to said devices, and means disposed between each of said devices and said first means and operatively connected to said devices for normally holding the same in an inoperative, out-of-the-way position and for shifting the same to an operative position upon the discharge of the pump thereto, said shifting means being operable to render said lifting means active.
14. A vehicle hydraulic system having connected therein a pump, a reservoir, a plurality of lifting devices operatively disposed on the vehicle for lifting the same, distributing means selectively connected to said device, controlling means connected with said first means, pump and reservoir for permitting said pump to discharge to either said first means or the reservoir, and means disposed between each of said devices and said first means and operatively connected to said devices for normally holding the same in an inoperative, out-of-the-way position and for shifting the same to an operative position upon the discharge of the pump thereto, said shifting means being operable in a predetermined position to render said lifting means active.
15. A vehicle hydraulic system having connected therein a pump, a reservoir, a plurality of lifting devices operatively disposed on the vehicle for lifting the same, means for selectively connecting said pump to said devices, and means disposed between each of said devices and said first means and operatively connected to said devices for normally holding the same in an inoperative, out-of-the-way position and for shifting the same to an operative position upon the discharge 130

of the pump thereto, said third means including a rotatable member rigidly secured to each of said devices and operable therewith, said rotatable member having a rigid support connected to the vehicle.

16. A vehicle hydraulic system having connected therein a pump, a reservoir, a plurality of lifting devices operatively disposed on the vehicle for lifting the same, distributing means selectively connected to said device, controlling means connected with said first means, pump and reservoir for permitting said pump to discharge to either said first means or the reservoir, and means dis-

posed between each of said devices and said first means and operatively connected to said devices for normally holding the same in an inoperative, out-of-the-way position and for shifting the same to an operative position upon the discharge of the pump thereto, said last mentioned means including a rotatable member rigidly secured to each of said devices and operable therewith, said rotatable member having a rigid support connected to the vehicle.

In testimony whereof I have hereunto subscribed my name.

HENRY GUSTAV EISLER.
